UNITED STATES PATENT OFFICE

MAX GRUNE, OF FIRMASENS, GERMANY

APPARATUS FOR THE MANUFACTURE OF PATTERNS FOR PRESSING MOLDS AND STAMPS

Original application filed October 5, 1926, Serial No. 139,741, and in Germany October 6, 1925. Divided and this application filed December 20, 1927. Serial No. 241,412.

- This application is a division of my co-pending U. S. patent application Serial No. 139,741, filed October 5, 1926, now Patent No. 1,724,473. In my said original application I have described a method of manufacturing paste-board shoe forms or lasts according to which the lasts or forms are manufactured in a stamping machine, working with specially designed stamping molds and dies and producing completely finished filling lasts or forms from one piece of paste-board in one phase. The stamping molds and dies used for the said purpose are cast preferably of iron, and my present invention relates to an apparatus whereby patterns or molds may be manufactured from which the said pressing molds and dies may be cast by using the patterns for making sand molds in which the molten iron is cast.
- The apparatus preferably consists of a vertically movable table, carrying a casting mold opposite which is located a carrier universally adjustable and capable of being secured in adjusted position as hereafter fully described.
- An apparatus designed according to this invention is shown diagrammatically and by way of example in the accompanying drawings in which
- Figure 1 is partly a side view of and partly a vertical section through a device for making a pattern,
- Figure 2 is a front view of this device,
- Figure 3 is a similar representation showing the manufacture of another part of the pattern,
- Figure 4 is a partial plan of Figure 3, the uppermost members of this figure being removed,
- Figures 5-7 are special illustrations of the mold H of Figure 3 in an enlarged scale, Figures 5 and 6 being vertical sections and Figure 7 a plan,
- Figure 8 is a side view of a portion of the machine showing a portion thereof in section.
- Referring first to Fig. 8, a is a pressing or stamping table which is vertically guided between two vertical standards of the frame 2 of a crank press. The bow-shaped upper part of the frame which is carried by the two vertical standards mentioned encloses in its uppermost or center portion a spindle b from which is suspended a vertically adjustable guide member c. The spindle b is provided with an external thread engaging an internal thread of a socket 9 having an upwardly extending pivot 10, the projecting portion of which is threaded and carries a counter nut 12 on this thread, and the end proper of which forms a square 11 adapted to receive a wrench, by which the pressure existing between the stamping members may be regulated.
- The guide member c carries two bell-crank levers d, the lower arms of which are subjected to the pressure of springs e constantly tending to hold said levers in the position shown. The guide member c carries also centrally a vertically shiftable pivot f having an enlarged head located below the ends of the upper arms of said bell-crank levers. The pivot f is normally maintained in its lowermost position by the pressure of the springs e. The pivot f projects downwardly below the guide member c and holds an exchangeable pressing stamp g.
- The table a carries the stamping mold which consists of three main parts h, i and k, of which h is provided with an upper cavity corresponding to the shape of the upper portion of the filler to be made, so that the finished filler can be removed upwardly. The other two stamp members i and k serve to shape the lower portion of the filler, one of them shaping the right half, the other the left half thereof. The stamp member h is located in a box m and the stamp members i and k are located in two lateral frames n and o. The members h, i and k can be exchanged for similar members of a more or less other configuration, as every other shape of filler necessitates stamp parts of corresponding other shapes. But the exterior dimensions of all stamp parts, irrespective of their different shapes in detail, are the same so that one set of boxes or frames m, n, and o will do for all stamp parts. The lateral frames n and o are guided separately by guide members p and q attached to the box m, Fig. 8;

besides they are kept in contact with abutment members *s* by strong springs *r*.

The molding or shaping parts *h*, *k* and *i*, as well as the stamp or die *g* may consist of any suitable material, preferably cast iron.

The manner of operation of the machine is as follows:

- When the table *u* is in its lowermost position, a piece *t* of paste-board in a dry state 10 or another suitable material and having the suitable size and shape as requisite for the filler to be made is placed upon the mold, and the machine started. The stamp *g* hereby enters the shaping mold and presses the piece 15 *t* into it. When the bottom of the shaping mold *h* contacts with the lower end of the stamp *g* (it being understood that the piece *t* of paste-board or the like is between the mold bottom and the stamp), the mold lifts 20 the stamp, as well as the pivot *f* whereby the bell-crank levers *d* are turned. In other words: the vertical arms of these levers shift the frames *n* and *o* and, by the intermediary of these frames, also the mold parts *k* and *i* 25 against each other so that the springs *e* are now compressed and the lateral rims of the piece *t* are pressed against the opposite rims of the stamp *g* whereby the pressing and shaping of the paste-board filler is finished.
- 30 This method of manufacturing the shoe-forms from paste-board is claimed in my said prior application and does not form a part of the present invention. The invention relates, as stated above, to an apparatus whereby 35 patterns may be manufactured from which the said molds *h*, *i* and *k* and the said die *g* may be cast by using said patterns for making a sand mold. This apparatus is shown in Figures 1 to 9 in which a stationary table 40 *U* is provided from which extend upwardly two standards *V* connected at their upper ends by a traverse *W*. Centrally in this latter a bolt *Y* is held in a ball-joint *X*. The bolt *Y* is provided with a transverse hole in 45 which a bracket *Z* is inserted. This bracket and bolt may be clamped in a vertical direction by means of a bolt *Y*¹ screwed through the bolt *Y* in such a manner that the bolts *Y* and *Y*¹ are prevented from being shifted in 50 an axial direction. The ball-joint may be fixed in the adjusted position by a screw *Y*² screwed through the traverse *W*. Attached to the projecting lower end of the bracket *Z* for instance, by screws, is a wooden last *A*. 55 A vertically adjustable and exteriorly threaded spindle *C* extends through the table *U* and is prohibited from being rotated by means of a bolt *L* screwed into a projection of the table *U* and engaging a groove *M* extending along 60 the spindle *C*. The spindle, however, can be moved up and down, as required by a hand wheel *B*, having internal screw-thread engaging the spindle *C* and being prevented from axial movement by suitable means, f. i. 65 by the weight of the parts supported by the

spindle *C*. The spindle carries on its top a plate *D*. The upward movement of this plate can be limited by a nut *E* located upon threaded portions of the standards *V* and being adjustable thereon. The plate *D* is 70 provided with guide ledges *F* between which may be placed a casting box *G* (Figs. 1 and 2). The inner dimensions of this box are somewhat larger than the inner dimensions of the box *m* shown in Figure 8. The casting box *G* is to be so adjusted in height by means of the hand-wheel *B* that the lower portion of the last *A*, i. e. that portion which is to extend later on into the said shaping mold *m*, extends into the casting box *G*. 80

The wooden last *A* is manufactured in correspondence of the original last with which the shoes for which the paste-board forms are designed are manufactured, however, its size is by so much longer than the original last as 85 corresponds to the shrinking of the cast piece. The last *A* is accurately adjusted by means of the ball-joint *X* and then fixed in its position by the screw *Y*². Then the abutment nuts *E* are adjusted upon the standards *V* so that the 90 upward movement of the table is properly limited, and now the mold *G* is filled with gypsum. Those surfaces of the last *A* and the mold *G* that come in contact with the gypsum have been previously treated in 95 known manner in order to render easy removal of the cast piece of gypsum from the box *G* possible. Thereafter the plate *D* with the box *G* thereon is so much lowered by means of the hand wheel *B* that the mold 100 with the gypsum therein leaves the last *A*. Now the box can be withdrawn from the guide ledges *F* and the plate *D* and the pattern *N* of the part *h* of the pressing mold shown in Figure 8 removed from the box *G*. 105 From this pattern the said mold or die part *h* is cast in any known manner, whereby preferably cast iron is used, e. g. by using the pattern *N* to make a sand mold in which the molten iron is cast. 110

After the casting box *G* has been removed from the plate *D* another, higher box *H*, Fig. 3 is shoved between the ledges *F*, and the plate *D*, is again so much lifted as to contact with the abutment nuts *E*. This mold *H* is 115 filled with dry sand up to the shoulder *J* (Figs. 3, 5 and 6) and a partition wall *K* (Figs. 4 to 7) of thin sheet-metal is inserted above the last *A* that lies within the mold *H*. The mold portion remaining on each side of the partition wall and located above the sand is filled up with gypsum. After the moistened gypsum has hardened there are obtained two patterns *o* and *p* which can simply be taken off the wooden last and the box *H* and serve afterwards for the casting of the shaping mold parts *i* and *k* shown in Fig. 8 from iron or the like. 125

The wooden last *A* itself serves as a pat- 130

tern for the casting of the pressing stamp *g*.

I claim:

An apparatus for the manufacture of patterns for a pressing mold and stamp for the manufacture of forms or lasts for shoes and boots from paste-board, fibrous substance or other material capable of being stamped, comprising a vertically adjustable table, an enlarged last above said table, a carrier adapted to carry said last, means for adjusting said carrier in all directions and for fixing it in any adjusted position, a casting box arranged on said table below the said last and comprising a lower portion to be filled with an inert material and an upper portion adapted for casting the patterns for lateral mold members, and a partition piece adapted to be inserted into the box, forming with the upper box portion spaces corresponding to said patterns for the lateral mold member.

In testimony whereof I have affixed my signature.

MAX GRUNE.
